UNITED STATES PATENT OFFICE.

FRANK V. CARMAN, OF OAKLAND, CALIFORNIA.

SPIKE-HOLE-PLUG MACHINE.

No. 908,950.

Specification of Letters Patent.

Patented Jan. 5, 1909.

Application filed December 23, 1907. Serial No. 407,873.

To all whom it may concern:

Be it known that I, FRANK V. CARMAN, a citizen of the United States, residing at Oakland, in the county of Alameda and State of California, have invented certain new and useful Improvements in Spike-Hole-Plug Machines, of which the following is a specification.

My invention relates to machines for making spike-hole plugs, such as are used to fill the holes in railway cross ties, after the spikes originally driven to hold the rails are, for any reason, drawn out; the object of the filling being to restore the holding capacity of the ties for fresh spikes or re-driving of the old ones.

The object of my invention is to provide a simple and effective machine for rapidly and accurately cutting and pointing groups or clusters of said plugs in the ends of blocks of wood, and then dismembering the groups and collecting the severed plugs.

My invention consists in the novel construction of parts and in their arrangement and combination, as I shall hereinafter fully describe, by reference to the accompanying drawings in which—

Figure 1 is a plan of my machine. Fig. 2 is an elevation of one side of the machine. Fig. 3 is an elevation of the other side of the machine. Fig. 4 is a foot-end elevation of the machine. Fig. 5 is a perspective view of one of the pockets of the block-carrier. Fig. 6 is a side elevation, partly broken, of the rip-saw gang and pointing knives. Fig. 7 is a front view of the same. Fig. 8 is a perspective view of a block of wood, broken, and showing the completion of a group or cluster of plugs made in one end, prior to the dismemberment of the group.

1 is the frame of the machine.

2 is the block-carrier composed of an endless series of pockets 3 connected by hinged lugs 4, said carrier being mounted upon terminal drums 5 and 6 as shown in Fig. 2.

7 is a vertical arbor upon which is mounted a horizontally-disposed gang of rip-saws 8, in any desired number, said gang rotating in a plane above the block-carrier and partially overlapping said carrier, as seen in Fig. 1, to the extent to which the saws are intended to cut into the blocks from which the plugs are to be made. The several saws of the gang are spaced apart to cut the desired thickness of the plugs,

and said spacing is had and maintained, as shown in Figs. 6 and 7, by intervening plates 9 which form heads for the point-cutting knives 10, which lie beside and between the saws in position to form the points of the plugs.

11 is a horizontal shaft, (Fig. 1) which carries the vertically disposed saw 12, Figs. 2 and 3, for cutting off the plugs from the block.

13 is a conveyer belt, Fig. 1, for receiving the plugs when cut off by saw 12, and conveying them to the sack 14 at the foot of the machine.

15 is a hold-down device for the blocks. This may be of any suitable character. In the form shown it consists of a series of springy tongues cut in a wooden strip and properly mounted above the block-carrier 2 in position to rest upon and hold down the blocks as the pockets of the carrier present them to the action of the rip-saw gang 8 and pointing knives 10.

Before pointing out further details, it will be well to describe the operation of the machine.

In Fig. 8 is shown a block of wood B, from one end of which has been ripped and pointed a group or cluster of plugs P which have not, as yet, been cut off from the block. A block, such as B, before any cuts have been made in it, is placed, by the operator, in a recumbent position, in one of the pockets 3 of the carrier 2, as is shown in Fig. 2. In this pocket it is well held by the flanges of the pocket, its inner end being in position to follow a path to the rip-saw gang 8, as is shown in Fig. 4. The carrier 2 moves the block forward, and said block passing under the springs 15 is firmly held down in the pocket and is thus presented to the saws 8.

By these saws a series of horizontal kerfs are made in the end of the block, to the required depth, and, at the same time, two bevels are taken off the ends of the ripped slabs, by the pointing knives 10. As soon as the block passes the saw gang 8, and before it reaches the cut-off saw 12, the operator lifts it out of the pocket, turns it in his hand through a quarter turn, and so turned replaces it in another pocket of the block-carrier, in advance of the hold-down 15 and saw-gang 8. Once more it is presented to the saw-gang 8, which now makes in it a series of cuts at right angles to the first series, and the pointing knives 10 cut off the remaining bevels;

and thus the block is cut as in Fig. 8, with a group or cluster of, as yet, unsevered plugs P. Now as the block leaves the saw-gang 8, the operator pushes it forward in the pocket, so that its cut end lies above the conveyer belt 13 and the bases of the plugs lie in line with the saw 12. In this position it is advanced by the carrier pocket to the saw 12 which cuts off the plugs from the block. 10 The severed plugs are now carried by the conveyer belt 13, upon which they drop, to the sack 14. The unused part of the block is removed and replaced in the carrier 2 for a repetition of the operation, and so forth, 15 until the block is used up.

As will be seen from Fig. 5, the pockets 3 of the block-carrier are open-topped and open-ended and are provided with side flanges which are reduced in height near the 20 inner end so that the rip-saws may operate on the block end, the body of the block being well held by the flanges. The open top and ends of the pocket enable the operator to place a block in it easily, and to remove it 25 freely, and also to slip it forward through the inner end, to present its group of plugs to the cut-off saw.

The several power transmitting connections will now readily be understood.

30 Power is led into the machine through the main counter-shaft 16 at the head of the frame, said shaft having the usual fast and loose pulleys at 17, Fig. 1. A belt 18 from a pulley 19 on shaft 16 leads to a pulley 20 on the vertical arbor 7, by which means the rip-saw gang 8 is driven. A belt 21 from a pulley 22 on shaft 16 leads to a pulley 23 on the horizontal shaft 11, by which means the 35 cut-off saw 12 is driven. Fig. 1. A belt 24 from a pulley 25 on shaft 16 leads to a pulley 26 on an intermediate counter-shaft 27; and from a pulley 28 on said counter-shaft a 40 belt 29 leads to a pulley 30 on a shaft 31 at the foot of the machine, which said shaft 31 carries the foot drum 6 of the block-carrier 45 2; and thus said carrier is driven.

In order to control the travel of the block-carrier, to stop and start it at will, there is a 50 gravity belt-tightener pulley 32 mounted on a pivoted frame 33, Fig. 3, and adapted to rest normally upon and tighten the belt 24 which transmits power from the main counter-shaft 16 to the intermediate counter-shaft 27. Mounted in frame 1 is a cross 55 shaft 34, Fig. 1, having on one end a handle 35, Figs. 1 and 2, and a ratchet 36 controlled by a pawl 37. The shaft 34 carries a pulley-crank 38, Fig. 1, from which a line 39 extends down to the pivoted frame 33 of the 60 belt tightener 32, Fig. 3. By operating the handle 35, the belt tightener may be raised or adjusted to fully control the movement of the block-carrier.

The conveyer belt 13 is mounted on terminal rolls 40 and is driven by a belt 41

leading from the intermediate counter-shaft 27 to one of the terminal rolls of said conveyer belt.

Having thus described my invention, what I claim as new and desire to secure by Letters-Patent is,

1. In a machine of the character described, the combination of an endless carrier comprising a hinged series of separate horizontally disposed transversely extending pockets to receive, hold and advance the blocks, said pockets being open at the top and ends, each of said pockets having two side members and a bottom member secured together to provide a rigid structure and arranged to permit lateral adjustment of the blocks in the pockets, a gang of horizontally disposed saws arranged for rotation in the plane above the carrier and overlapping the carrier to extend in the path of travel of the inner ends of the blocks to cut in the block ends a group of plugs, and a vertically disposed cut-off saw arranged to operate in a plane immediately adjacent one side edge of the carrier and the inner ends of the pockets.

2. In a machine of the character described, the combination of a carrier comprising a series of horizontally disposed pockets to receive, hold and advance the blocks, said 95 pockets being open at the top and ends and having side flanges reduced in height at their inner ends, a gang of horizontally disposed saws, rotating in a plane above the carrier and overlapping the carrier to extend in the path of travel of the inner ends of the blocks to cut in said block ends a group of plugs, a vertically disposed cut-off saw adjacent one side of the carrier, and a conveyer for the severed plugs extending 100 along one side of the cut-off saw to one end of the machine.

3. In a machine of the character described, the combination of a carrier comprising a series of open top horizontally disposed 110 pockets arranged to travel in a horizontal plane to receive, hold and advance the blocks, a gang of horizontally disposed saws rotating in a plane above the carrier and overlapping the carrier to extend in the path of travel of the inner ends of the blocks to cut in the block ends a group of plugs, a vertically disposed cut-off saw, and means extending above the carrier over the 115 gang of horizontally disposed saws to hold the blocks down in the pockets as they are presented to said gang of saws.

4. In a machine of the character described, the combination of a carrier comprising a series of open top horizontally disposed 125 pockets arranged to travel in a horizontal plane to receive, hold and advance the blocks, a gang of horizontally disposed saws rotating in a plane above the carrier and overlapping the carrier to extend in the 130

path of travel of the inner ends of the blocks to cut in the block ends a group of plugs, a vertically disposed cut-off saw, and means for holding the blocks down in the pockets as they are presented to the gang of saws, said means comprising a strip provided with a plurality of spring tongues, said strip being supported above the carrier to extend over the gang of saws, so that

the spring tongues of the strip engage and hold down the blocks in the pockets.

In testimony whereof I have signed my name to this specification in the presence of two subscribing witnesses.

FRANK V. CARMAN.
